UNITED STATES PATENT OFFICE.

HENRY ROBERT SAMSTAG, OF NEW YORK, N. Y., ASSIGNOR TO SAMSTAG & HILDER BROS., INC., OF NEW YORK, N. Y., A CORPORATION OF NEW YORK.

DESIGN FOR A BLANK OF LEATHER.

Application filed December 15, 1925. Serial No. 15,760. Term of patent 3½ years.

To all whom it may concern:

Be it known that I, HENRY ROBERT SAMSTAG, a citizen of the United States, residing at New York city, in the county of New York and State of New York, have invented a new, original, and ornamental Design for a Blank of Leather, of which the following is a specification, reference being had to the accompanying drawing, forming part thereof, in which the figure is a plan view of a blank of leather showing my new design.

I claim—

The ornamental design for a blank of leather substantially as shown.

HENRY ROBERT SAMSTAG.
